JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE.

TYPEWRITING MACHINE.

Application filed October 28, 1926. Serial No. 144,704.

This invention relates to a novel twin fan-fold typewriting machine, and more particularly to novel means whereby two fan-fold carriages may be used either singly or 5 jointly.

In an ordinary fan-fold machine, a work-web interleaved with carbons is positioned around the platen. After typing a form, the platen is elevated to straighten out the 10 web, and the carbons are stripped or moved back to a fresh work-web section. After this, the platen is lowered to its normal position and the typed form is gaged and severed against a knife.

15 For simultaneous use of two different forms of web, provision is made of two platens, each carrying a web, the carriage being moved to present either web to the printing field. There are provided two normally-joined carriages which may be disconnected, so that when desired either of the 20 carriages may be operated separately, the carriage not in use being held stationary at one side of the machine. This novel type 25 of machine is especially adapted to turn out a variety of work, such as, for instance, work calling for successively typing a letter on each form, in which case the two carriages are operated jointly. Sometimes, the 30 work may require the typing of one or more forms on one of the carriages or carriage-sections, and then the typing of one or more forms on the other carriage. In this latter 35 case, much effort is saved the operative by disconnecting the two carriages or sections and by operating each one singly as a complete unit.

The two carriages are controlled by the 40 same line-spacing mechanism and are fed in letter-space direction by means of a spring-drum which is operatively connected to both carriages by means of a tape pulling on a double-acting cord fast to both carriages. By means of this arrangement it is 45 possible to hold either of the carriages or sections out of the printing field while the other carriage is operated in the printing field.

50 One of the features of this invention relates to means for easily and accurately hooking the two carriages to be operated jointly. To this end, a manually-operable clamp is pivotally mounted on one of the carriages. This clamp engages with a fixed

member carried by the other carriage. The 55 two carriages are held a predetermined distance apart by means of a spacing block adjustably mounted on one of the carriages which abuts against the frame of the other carriage.

60 Another feature of this invention relates to means for disconnecting the carriages from the escapement-mechanism in order that said carriages may be positioned. Each carriage-feeding rack is provided with a handle and may be independently operated when the carriages are operated singly, but when the carriages are joined the operation of either rack is effective to operate the other also.

65 In order that either carriage may be moved to the printing field without re-positioning the marginal stops which limit the movement of the carriage within the printing field, it is proposed to swing the left-hand marginal stop in order to let the left-hand carriage pass to its ineffective position.

70 It will be understood that, while the left-hand carriage may be held against a fixed stop in its ineffective position under the 80 tension of the spring-drum, the right-hand carriage, when free of the escapement-device, must be locked in its ineffective position against the pull of said spring-drum in order that the left-hand carriage may be 85 operated. It is another feature of this invention to provide such a lock for holding the right-hand carriage.

75 Another feature of this invention is that 90 a pair of standard carriages may be mounted side by side upon extra-long carriage-guide-ways. Since the frame of the machine need not be changed, it is possible to re-equip old machines with the present improvements by simply providing new guide-ways having opposite extensions and an extra carriage, said extensions affording sufficient range of letter-feeding travel for 95 either carriage, and also permitting either carriage to be shifted clear of the type-system and escapement-device.

100 Other features and advantages will hereinafter appear.

In the accompanying drawings,

105 Figure 1 is a perspective view of a twin-platen Underwood fan-fold machine, and shows the means for hooking the two carriages together.

Figure 2 is a plan view, showing the two carriages joined to be operated as a unit, the left-hand platen being in printing position.

6 Figure 3 is a side view, in elevation, showing the upper part of the typewriter and the carbon-carriage at the rear thereof.

Figure 4 is a diagrammatic view, showing the right-hand carriage in typing position, 10 and the left-hand carriage in its inoperative position.

Figure 5 is a similar view, showing the left-hand carriage in typing position, and the right-hand carriage in inoperative position.

15 Figure 6 is a diagrammatic view, showing the spring-drum for operating both carriages either singly or jointly.

Figure 7 is a detail perspective view, showing the means for connecting the two carriage-feeding racks to be operated together.

Figure 8 is a back view of the machine, showing the means for assembling the two carriage-feeding racks.

20 Figure 9 is a detail showing the locking means for the right-hand carriage.

The present improvements include a machine provided with two carriages 10 and 11, both being slidably mounted on rails 30 12 and 13. The method of operating the machine is to draw a multiple-ply web 14 from a supply at the rear of the machine, and to pass the web over a cross-bar 16 mounted at the rear of a frame 17, which 35 travels together with the carriage. The frame is supported at the rear thereof by means of rollers 15 bearing on a cross-rail 18. Prior to inserting the web around the platen 19 to be typed, the plies thereof are 40 interleaved with carbons 20, which are secured to a carbon-carrier 21, and the assembled web is inserted around the platen to typing position. After typing a form, the platen may be swung about a shaft 22 to 45 straighten out the web and thereby enable the carbon-carrier to be moved rearwardly to shift the carbons. While stripping the carbons, the web is pulled forwardly against a gage 23, and then the platen is lowered to 50 its normal position, and the typed form is torn off against a knife, not shown. The usual means whereby the platen may be swung about said shaft 22 are partly shown, and are fully set forth in Patent 1,175,945 55 to B. P. Fortin, issued March 21, 1916. Said patent also shows the web-severing means. Each platen is provided with independent line-spacing mechanism, including a knob or finger-wheel 80 for each platen 60 and line-spacing levers 81 which are operatively connected to line-spacing wheels 82 fastened to shafts 83 journaled in end plates 84 of the platen-frame. Said shafts 83 are in turn operatively connected to platen-axles 84^a, by means of gears 85 and

86, and co-operating pinions 87 secured to the shafts 22. It will be seen that, when the platen, mounted in a swingable frame 98, Figure 3, is swung upwardly about shaft 22 to straighten the web, the platen-axle 70 gears 86 are caused to roll around the pinions 87, which are held stationary by reason of their connection with the detented line-space wheel, thereby keeping the platen permanently connected to the line-space wheel, 75 as set forth in said patent.

It will be understood that both carriages are preferably of a standard Underwood construction. The carriage-rails 12, 13 and 18 are provided with opposite extensions 12^a, 80 13^a and 18^a, respectively. Said extensions are of such length that there is afforded for either carriage a sufficient range of letter-feeding movement to permit full-width typing of an ordinary work-sheet, while the 85 other carriage is moved entirely out of typing position away from the type-system. The extensions are further of such length that the carriage to be moved away from the typing position may be moved sufficiently to 90 disconnect it from the usual letter-feeding mechanism to be later described. Different work-sheets may therefore be presented alternatively to the type-system at will, while retained in typing positions in their respective carriages.

In some classes of work it is desired to first type a line on one of the webs, and then to type another line on the other web. In this case it is advantageous to hook the two 100 carriages together, so that both may be returned to typing position in one operation. Other classes of work, however, call for the typing of a whole form on one of the webs. In this case, it has been found that it is easier for the operator to hold the carriage not being used stationary and to operate the other carriage singly. To these ends, a pair of latches 24 are carried by a shaft 25 mounted on brackets 26, fast to one of the 105 carriages by means of screws 27. Said latches engage with locking plates 28, which are fast to the other carriage by means of screws 29. Normally, the latches are held in their operative or closed position, as 110 shown in Figure 1, by means of a spring 30 wound around the shaft 25. The latches are swung to ineffective position by means of a finger-piece 31, to thus permit independent 115 operation of the carriages. In order to provide a solid connection between the two carriages, there may be provided a spacing block 32 adjustably mounted on one of the carriages by means of nuts 33. This spacing block abuts against the other carriage to hold 120 the two carriages a predetermined distance apart. The rocking movement of the shaft 25 is limited by a plate 34, which is fast to the shaft 25 and carries pins 35 designed to 125 engage one of the brackets 26.

The two carriages are operated in letter-space direction by means of a common spring-drum 37, which is pivotally mounted on a stud 38, carried by a plate or bracket 36. This drum carries a tape 39 wound therearound, and the free end of the tape is provided with a pulley 40. Said pulley is operatively connected to both carriages by means of a cord 41, which is fast by 10 means of screws 42 and 43, respectively, to the carriages 10 and 11. The cord is passed over a pair of pulleys 44 and 45, rotatably mounted on studs carried by a plate 46, fast to the frame of the machine, as shown in 15 Figure 6. By means of this arrangement it is possible to letter-space both carriages simultaneously, or to hold either one of the carriages while the other one is being letter-spaced. In Figure 4 the carriage 10 is held 20 stationary at the left-hand side of the frame, while the carriage 11 is shown in operating position at the printing field. In Figure 5 the carriage 11 is held stationary at the right-hand side of the frame, while the carriage 10 is shown in operating position.

It is well known that the Underwood machine is provided with means for releasing the carriage in order that the same may be positioned independently of the letter-spacing mechanism. Said means include an escapement-rack 47, which engages with an escapement-wheel 48. The latter is controlled by other portions of the escapement-mechanism, not shown, and in turn controlled by the type-bars. The racks are secured to levers 49, having handles 52, and the levers are pivotally mounted on studs 50, fast to the carriage. In this machine there is only one escapement-mechanism 30 provided, which co-operates with either of the carriages. In order that the two escapement racks may be simultaneously operated from either of the carriages to release said carriage from the escapement-device, it is 40 proposed to connect the two racks by means of a sliding plunger 51 carried by one of the racks, which engages a hole 50^a in one of the levers 49. This plunger is held in engaged position by means of a spring 53, 45 and is held in its normal position when the two carriages are disengaged by means of a collar 54.

Since the two carriages are always urged in letter-space direction by the force of the 50 spring-drum 37, it will be seen that while the carriage 10 can be held in its ineffective position against a stop 97 by the force of the spring, the carriage 11 must be locked in its ineffective position in order to prevent 55 accidental displacement thereof. The locking means for this carriage 11 may include a latch 56 mounted on one of the racks 47, which operates with a stop-device or collar 57. Said collar may be fast to the rail 13 60 by means of a pin 58. This latch is auto-

matically released when the rack 47 associated with the carriage 11 is swung to release the carriage, but is not affected when the other rack is so swung to release its carriage in the independent operation thereof. 70 Thus the release of the carriage 11 from its idle position is automatically accomplished by raising its rack 47, such raising of said rack being necessary anyway, on account of the one-way action of the escapement-device, before the engagement of the carriage 11 with said escapement-device may be effected. 75

It will be noted that by reason of the yieldable spring-pressed carriage-connecting 80 mechanism, of which the latches 24 and plunger 51 form a part, either carriage may be connected to the other by merely bringing said either carriage into juxtaposition with the other carriage. As they are 85 brought into said juxtaposition for joint operation, the latches 24 will automatically snap into holding position over the plates 28, and the plunger 51 will automatically engage the hole 50^a. The rack-connecting 90 means is made yieldable because, when the carriage 11 is moved to bring it into juxtaposition with the other carriage, its rack 47 will necessarily have to be raised, in which case the plunger 51 would not align with the 95 hole 50^a of the other carriage until the rack 47 is released again. As said release may not take place until the carriages are actually in juxtaposition with one another, the plunger 51 yields as the end thereof encounters the lug surrounding the hole 50^a. It is obvious that as soon as the rack 47 is released the plunger 51 automatically enters the hole 50^a, thereby automatically establishing connection between the racks 47. 100 Disconnection of either carriage from the other is effected by merely pressing the finger-piece 31 and then separating the carriages to the extent desired. 105

The machine is provided with marginal 110 stops 59 and 60 for limiting the travel of the carriage. The stop 59 controls the left-hand margin of the paper, and may be set in relation to a scale 61 by means of finger-pieces 62. When returning the carriage to 115 start a line, the same is arrested by a lever 63, which strikes a lug 64 carried by the stop 59. Said lever is pivotally mounted on a screw 65, and is held in its normal position by means of a spring 66. In order that the carriage may be jumped over said stop 59 without disturbing the position thereof, the lever 63 is provided with an extension 67, which protrudes through the frame of the carriage at a point near a carriage-return handle 68. When the extension 67 is depressed, the carriage may be moved past the stop 59, to its inoperative position. The left-hand marginal stop 60, 120 which controls the right-hand margin of the 125

paper, may be similar to the stop disclosed in my patent No. 1,599,795, dated September 14, 1926. The stop shown in said patent is not only effective to operate a carriage-alarm when nearing the end of a line, but is also effective to lock the type-keys, to thus prevent further typing when the end of the line is reached. In addition to this, it is possible to render the stop ineffective and permit the passing of the carriage 10 to its inoperative position. In this invention, the stop 60 is merely illustrative, and shows only the means for stopping the carriage upon reaching the end of a line. This stopping means includes a plate 69, which co-operates with a lug 70, forming an integral part of the carriage-frame. Both marginal stops are slidably mounted on a cross-shaft 71, and are positioned by a rack 72. The latter is pivotally mounted on the shaft 71, and is held in its effective position by a spring 73. In order that the carriage 10 may be moved to its ineffective position, the stop 60 and the rack 72 associated therewith are swung downwardly by means of a finger-piece 74 carried by the stop 60.

Either carriage may be positioned to typing position by operation of a tabulator-key, not shown, which is effective to release the carriage from the escapement-mechanism, and to elevate a plunger 75 in the path of a tabulating stop 76 carried by a toothed cross-bar 77. Said cross-bar is mounted on the carriage, and the stops are positioned thereon by means of a co-operating scale 78, which is supported on end-brackets 79 fast to the bar 77. The latter is graduated to correspond with the scale 61 at the front of the machine. It will be understood that there is provided a scale 78 for each carriage, both co-operating with the front scale 61. In this manner the tabulating stops on each carriage may be adjusted independently of each other, both settings corresponding to the position of the marginal stops, which are positioned relatively to the front scale. The type of tabulating mechanism herein represented is fully described in Patent No. 956,144 to J. C. McLaughlin, dated April 26, 1910. There may be only one plunger 75 if ordinary column-skipping only is to be effected. It will be understood that any other type of tabulating mechanism may be used within the scope of the invention. In some forms of the invention, as for example, where there is, in the joint operation of the carriages, a considerable gap between the platens, as in the machine herein illustrated, the gap may be caused to quickly traverse the printing field by means of the tabulating mechanism, aside from the use of said mechanism in quickly positioning either carriage while in the printing field. It will be seen that the

tabulating mechanism may be also used to release the left-hand carriage 10 from the printing field and effect the shifting thereof to ineffective position. A further use of the tabulating mechanism is as follows: Should the left-hand carriage 10 be in ineffective position and the carriage 11 be in the printing field, the tabulating mechanism may be operated to release the carriage 11 from the control of its escapement-mechanism, and permit it to be drawn by the spring-drum into juxtaposition with the carriage 10 to which it may become automatically connected for operation of said carriages as a unit. Thus, it will be seen that the tabulating mechanism forms a useful feature of the invention herein set forth.

It will be understood that these improvements are in the nature of an attachment to a standard Underwood machine having, as already stated, extended rails to accommodate the companion carriages. The rails are fast to a frame 88, which is provided with a rear extension 89 for supporting the extended rear rails 18. The spring drum 37 is operated by a spiral spring 90 which is wound around the stud 38. The latter is secured to the plate 36, in turn, fast, by means of screws 91, to the frame 88. This plate may be attached to any standard machine. The two pulleys 44 and 45 are rotatably mounted on studs respectively numbered 92 and 93 carried by the plate 46 which is fast to the frame 88 by means of screws 94. Said plate 46 carrying the pulleys is also attached to the machine as a separate unit.

The usual Underwood system of key-operated type-bars 95 striking at a common printing center, is conventionally represented, the usual key-board thereof being indicated at 96, Figure 2. It will be understood that these printing instrumentalities control the usual escapement-device represented by the escapement-wheel 48. One of the type-bars 95 is shown in printing position to indicate, in the several views, which one of the carriages is at the usual printing field.

Variations may be resorted to within the scope of the invention, and portions of the improvements may be used without others.

Having thus described my invention, I claim:

1. In a typewriting machine having a single set of printing instrumentalities, the combination of two platens, two letter-feeding carriages, one for each platen, and means whereby said carriages may be operated either together as a unit or each independently of the other by and in respect to said single set of printing instrumentalities.

2. In a typewriting machine, the combination of two platens, two carriages, one

for each platen, and means whereby each carriage may be operated either together as a unit or independently of each other, said means including a spring-drum, a tape wound therearound, a cord having one end attached to each carriage, and a pulley carried by said tape and actuating on said cord.

5 3. In a typewriting machine having a single set of printing instrumentalities, the combination of a plurality of carriages independently operable by and in respect to said printing instrumentalities, and releasable means enabling said carriages to be jointly operated as a unit.

10 4. In a typewriting machine having a single set of printing instrumentalities, the combination of two carriages independently operable by and in respect to said printing instrumentalities, releasable means for connecting the two carriages so that both carriages may be operated as a unit, and means for locking either of the carriages out of the printing field of said printing instrumentalities when the other carriage is operated.

15 5. In a typewriting machine, the combination of two independently-operable carriages, and means for hooking the two carriages, so that both carriages may be jointly operated, said hooking means including a latch pivotally mounted on one of the carriages, a device carried by the other carriage for co-operating with said latch, and spacing means between the two carriages for holding the carriages at a predetermined 30 distance.

20 6. In a typewriting machine having a single set of printing instrumentalities, the combination of a pair of independently-operable carriages for presenting different work-webs to said printing instrumentalities, and means for controlling the letter-spacing movement of said carriages in respect to said printing instrumentalities either independently or together as a unit.

25 7. In a typewriting machine, the combination of a pair of independently-operable carriages, and means for controlling the letter-spacing movement of both carriages either independently or together, said means including a spring-drum, a tape wound therearound, and means including a cord for operatively connecting said tape with both carriages, so that either carriage may be operated while the other one is held stationary.

30 8. In a typewriting machine having a single set of printing instrumentalities, the combination of two independently-operable carriages for presenting different work-webs to said printing instrumentalities, releasable means for hooking both carriages together for operation as a unit, and means for letter-spacing both carriages by said printing instrumentalities.

35 9. In a typewriting machine, the combination of two independently-operable carriages,

means for hooking both carriages together and means for letter-spacing both carriages, said hooking means including a latch fast to a shaft journaled in brackets carried by one of the carriages, locking means carried by the other carriage for cooperating with said latch, a spring to hold the latch in its latched position, and a handle for swinging the latch to its ineffective position.

40 10. In a typewriting machine having a single printing point, the combination of a frame, carriage-guideways on said frame, two independently-operable carriages slidably mounted on said guideways for movement past said printing point and a fixed scale carried by said frame, said scale being effective to position either of the carriages to the printing point.

45 11. In a typewriting machine having a single escapement device, the combination of two independently-operable carriages, each having a releasable letter-spacing rack co-operable with said escapement device, releasable means for hooking the two carriages together to be operated as a unit, and means for connecting the two letter-spacing racks, so that one rack is effective to release the other upon operation of said one rack to release the connected carriages from said escapement device.

50 12. In a typewriting machine, the combination of two independently-operable carriages, each having a releasable letter-spacing rack, means for hooking the two carriages together to be simultaneously operated, and means for connecting the two letter-spacing racks, so that one is effective to release the other upon operation thereof, said means including a spring-plunger mounted on one of the racks and a bracket carried by the other rack having a hole for receiving said plunger.

55 13. In a typewriting machine having a single printing field, the combination of two carriage-sections movable past said printing field, a tabulating mechanism for positioning either carriage-section in respect to the printing field, a scale for each carriage-section for positioning tabulating stops co-operating with said tabulating mechanism, and a single marginal scale effective for both carriage-sections and graduated to correspond with the tabulating scales for said carriages.

60 14. In a typewriting machine having a single printing field, the combination of two independently-operable letter-feeding carriage-sections, each movable past said field, and a pair of marginal stops effective to control the travel of either carriage-section within the range of its letter-feeding movement.

65 15. In a typewriting machine having a single printing field, the combination of two carriage-sections, each operable independently in respect to said printing field while

the other carriage is in ineffective position, a pair of marginal stops effective to control the travel of either carriage-section, and means associated with the left-hand marginal stop for manually rendering said stop ineffective so as to permit shifting of the left-hand carriage to its ineffective position.

16. In a typewriting machine having a pair of independently-operable carriages, each being operable in the printing field and each having an escapement-rack co-operating with a fixed escapement-wheel, said racks being disconnectible from the escapement-wheel to permit manual shifting of the carriage associated therewith, means for hooking the two carriages together, and means for automatically hooking the escapement-racks together so that either rack may be rendered ineffective when the other rack is operated.

17. In a typewriting machine having a pair of independently-operable carriages, each being operable in the printing field and each having an escapement-rack co-operating with a fixed escapement-wheel, said racks being disconnectible from the escapement-wheel to permit manual shifting of the carriage associated therewith, means for hooking the two carriages together, and means for automatically hooking the escapement-racks together so that either rack may be rendered ineffective when the other rack is operated, said last-mentioned means including a collapsible plunger carried by one of the racks and a block carried by the other rack, said block having a hole therein for receiving the plunger.

18. In a typewriting machine having two independently movable letter-feeding carriages, the combination with a single carriage-motor, of means enabling said single motor to drive either carriage while the other carriage is stationary.

19. In a typewriting machine having a single set of printing instrumentalities, the combination with two letter-feeding carriages, each independently movable in respect to said printing instrumentalities, of carriage-propelling means for letter-feeding either carriage while the other carriage is stationary.

20. In a typewriting machine having two independently-movable letter-feeding carriages, the combination with a single carriage-motor, of a differentially acting device automatically enabling said motor to drive either carriage while the other carriage is stationary.

21. In a typewriting machine having a single set of printing instrumentalities, the combination with a letter-feeding carriage for a work-web, of a second-letter-feeding carriage for another work-web, and means enabling either carriage to be brought into action in respect to said printing instrumen-

talities, so that typing may be done upon either work-web.

22. In a typewriting machine having a single set of printing instrumentalities, the combination with a letter-feeding carriage for a multiple-ply work-web, said carriage having a platen, line-spacing means, and devices enabling said platen to feed a multiple-ply work-web interleaved with carbon-sheets across the printing line, said devices including means carried by said carriage and operative for effecting the shifting of the carbon-sheet relatively to said work-web, of a second carriage also having a platen, line-spacing means and web-feeding and carbon-shifting devices as aforesaid, and means enabling either carriage to be brought into action in respect to said printing instrumentalities, so that while typing is being done on either work-web the other carriage may hold its work-web in stationary reserve ready for typing.

23. In a typewriting machine, the combination with a pair of carriages, each independently operable past the same printing field, each carriage having a letter-spacing rack co-operable with an escapement device, each rack being movable for disconnection from the escapement device to permit manual shifting of its associated carriage, of means whereby said carriages may be operated together as a unit, said means including rack-connecting means, whereby a carriage-releasing movement of one rack effects a similar movement of the other rack when the carriages are operated as a unit.

24. In a typewriting machine, the combination with a pair of carriages, each independently operable past the same printing field, each carriage having a letter-spacing rack cooperable with an escapement device, each rack being movable for disconnection from the escapement device to permit manual shifting of its associated carriage, of means whereby said carriages may be operated together as a unit, said means including rack-connecting means, whereby a carriage-releasing movement of one rack effects a similar movement of the other rack when the carriages are operated as a unit, said rack-connecting means being constructed to yield if one rack is displaced relatively to the escapement device when said carriages are brought into juxtaposition for joint operation and being further constructed to automatically connect said racks as the displaced rack assumes, in said juxtaposition, its normal position relative to said escapement device.

25. In a typewriting machine, the combination with a pair of carriages, each independently operable past the same printing field, of means whereby said carriages may be operated together as a unit, said means being constructed to automatically become

effective to connect and hold said carriages together as one carriage is brought into end-wise juxtaposition with the other.

26. In a typewriting machine, the combination with a pair of carriages, each independently operable past the same printing field, of means whereby said carriages may be operated together as a unit, said means being constructed to automatically become effective to connect and hold said carriages together as one carriage is brought into end-wise juxtaposition with the other, said means also being operable to permit the disconnection and separation of said carriages.

15 27. In a typewriting machine having a single set of printing instrumentalities, the combination with a letter-feeding carriage for a work-web and a letter-feeding escapement device controlled by said printing instrumentalities and effective upon said carriage, of a second letter-feeding carriage for another work-web, and means enabling the first carriage to be shifted from operative connection with said printing instrumentalities and escapement device, and also enabling the other carriage to be brought into operative connection with said printing instrumentalities and escapement device upon said disconnection of the first carriage.

30 28. In a typewriting machine having an escapement device, the combination with two independently-movable letter-feeding carriages, means for bringing either carriage into operative relation with said escapement device while the other carriage is disconnected from said device, and carriage-propelling means urging both carriages to move in a letter-feeding direction, of means for holding the disconnected carriage against the effort of the carriage-propelling means.

35 29. In a typewriting machine having an escapement device, the combination with a letter-feeding carriage normally controlled by said escapement device, means enabling said carriage to be shifted to a position in which it is disconnected from the escapement device, and carriage-propelling means always urging said carriage in a letter-feeding direction, of means for holding said carriage, in its disconnected position, against the effort of the carriage-propelling means.

40 30. In a typewriting machine having an escapement device, the combination with a letter-feeding carriage normally controlled by said escapement device, means enabling said carriage to be shifted to a position in a direction opposite to the direction of its letter-feeding travel for disconnection from the escapement device, and carriage-propelling means always urging said carriage in a letter-feeding direction, of means for releasably holding said carriage, in its disconnected position, against the effort of the carriage-propelling means.

45 31. In a typewriting machine having an escapement device, the combination with a letter-feeding carriage normally controlled by said escapement device, and having a rack cooperating therewith and being releasable therefrom for shifting the carriage to and fro, means enabling said carriage to be shifted to a position in which it is disconnected from the escapement device, and carriage-propelling means always urging 70 said carriage in a letter-feeding direction, of means co-operating with said rack to hold said carriage in its disconnected position against the effort of the carriage-propelling means.

50 32. In a typewriting machine having an escapement device, the combination with a letter-feeding carriage normally controlled by said escapement device, and having a rack co-operating therewith and being releasable therefrom for shifting the carriage to and fro, means enabling said carriage to be shifted to a position in which it is disconnected from the escapement device, and carriage-propelling means always urging 75 said carriage in a letter-feeding direction, of means co-operating with said rack to hold said carriage in its disconnected position against the effort of the carriage-propelling means.

55 33. A typewriting machine having, in combination, a type-system, a complete paper-carriage, letter-feeding mechanism, guide-tracks for said carriage, said carriage having sufficient range of letter-feeding movement along said guide-tracks to permit the full-width typing of an ordinary work-sheet, an extension of said carriage-guiding tracks of sufficient length to permit the carriage to travel thereon entirely out of typing position away from said type-system, and a companion complete carriage, said carriage-guiding tracks also having opposite 100 extensions of sufficient length to permit the movement of said companion carriage thereon entirely out of typing position away from said type-system, said extensions of sufficient length to permit each carriage to be moved out of the range of movement of the other, whereby different work-sheets may be presented alternatively to said type-system at 105 will while retained in typing positions in the carriages, said letter-feeding mechanism including means effective while either carriage is presented to said type-system and the other carriage remains idle in stationary position.

60 34. A machine as set forth in claim 33, having releasable means for connecting said carriages to travel as a unit.

65 35. A machine as set forth in claim 33, having provision for silencing the letter-feeding mechanism as to either carriage,

said mechanism being common to the carriages.

36. In a machine as set forth in claim 33, and in combination, a driving spring connected to drive either carriage while the other remains stationary.

37. In a typewriting machine having a single printing field, the combination with two independently-operable letter-feeding carriages, each operable in respect to said printing field while the other carriage is in ineffective position, removed from said printing field, of a pair of marginal stops for controlling the travel of either carriage within the range of its letter-feeding movement, and means associated with each mar-

ginal stop capable of rendering it ineffective, to permit shifting of either carriage to its ineffective position.

38. In a typewriting machine having a single printing field, the combination with two letter-feeding carriages, each having provision for carrying a work-web and being independently movable past the printing field for typing at will upon either work-web, and means enabling said carriages to be operated as a unit for typing upon said work-webs alternately, of tabulating mechanism effective for either carriage when operated independently and also effective for both carriages when operated as a unit.
